UNITED STATES PATENT OFFICE.

JOHN H. MADDEN, OF NEW YORK, N. Y.

GRINDING AND POLISHING WHEEL.

SPECIFICATION forming part of Letters Patent No. 287,144, dated October 23, 1883.

Application filed September 1, 1883. (No model.)

To all whom it may concern:

Be it known that I, JOHN H. MADDEN, of New York, in the county of New York and State of New York, have invented certain Im- 5 provements in Grinding and Polishing Wheels, of which the following is a specification.

My invention relates to that class of grinding-wheels the operative surfaces of which are composed of emery, corundum, or other abra- 10 sive material molded into suitable form.

It is the aim of the invention to lessen the cost of manufacture, to reduce the weight so that the wheels may be driven with less power and at higher speeds, and to avoid the liability of fracture and the loss and danger at- 15 tendant thereon.

To this end the invention consists in combining with a peripheral ring or rim a central supporting hub or disk of paper, and in the 20 peculiar manner of shaping and uniting said parts.

Referring to the accompanying drawings, Figure 1 represents a central cross-section of my improved wheel. Fig. 2 represents a side 25 elevation of the same.

Referring to the drawings, A represents the rim or grinding-surface of the wheel, made in the form of a ring or hoop, with an inwardly-extending flange, *a*, at one side.

30 B represents the hub or body, composed of paper, with its periphery shaped to fit the interior of the rim and seated firmly therein, the flange of the rim being seated in and against the side face of the hub, as shown.

35 C represents fastening-bolts, inserted transversely through the two parts for the double purpose of preventing their lateral separation and holding the rim so that in the event of its being fractured its parts will not be thrown 40 off by the centrifugal force developed. In place of the bolts other suitable connecting devices may be employed.

The rim may be molded of any of the various emery compounds known in the art, or of other suitable materials under pressure. 45

The hub or body is preferably constructed by subjecting superposed sheets of straw-board or paper to pressure, by a hydraulic press or otherwise, sufficient to unite them in a firm compact body. The hub is made of a diameter slightly greater than the interior of the rim, and is forced to its place therein, this procedure insuring an intimate contact between the parts and a firm support to the rim. 55

I am aware that grinding-wheels have been made with the removable rims mounted upon metal hubs and between metal clamps, and also that a soft-rubber ring has been introduced between a grinding-rim and a central hub, and I lay no claim thereto. 60

My paper body being light, moderately elastic, a non-conductor of heat, and unaffected by changes in temperature or by the presence of moisture gives to my wheel a 65 durability, efficiency, and uniformity of wear not secured by the use of any other material.

Having thus described my invention, what I claim is—

1. A grinding-wheel consisting of a ring of 70 abrasive material and a central hub of paper seated firmly therein.

2. The flanged ring of abrasive material, combined with the rabbeted paper hub and connecting devices, substantially as shown. 75

3. As a new article of manufacture, a grinding-wheel having a central hub or body of compressed paper and a rim of abrasive material, substantially as described and shown.

JOHN H. MADDEN.
